UNITED STATES PATENT OFFICE.

THOMAS F. BUCKLEY, OF SCRANTON, PENNSYLVANIA.

SPRING-FORMING MACHINE.

Original application filed October 9, 1924, Serial No. 742,598. Divided and this application filed December 16, 1925. Serial No. 75,745.

My present invention relates to spring forming machines of the general class or type set forth in Letters Patent of the United States No. 1,275,377, granted to Samuel S. Riegel and myself, August 13, 1918, and Nos. 1,428,626 and 1,459,045, granted to me September 12, 1922, and June 19, 1923 respectively and is a division of my copending Patent No. 1,572,639, granted February 9, 1926, for spring-forming machine. The object of my invention is to further improve the means for holding the formation plate and regulating the variation of temperature of the spring plates.

15 The improvement claimed is hereinafter fully set forth.

In the accompanying drawing: Figure 1 is a partial plan or top view of a spring forming machine, illustrating an embodiment of 20 my invention; Fig. 2, a view, partly in elevation and partly in section, of one of the presser blocks thereof; and, Fig. 3, a similar view, taken at a right angle to Fig. 2.

In the practice of my invention, referring 25 descriptively to the specific embodiment thereof which is herein exemplified, the leading and characteristic features of the means for bending or shaping the plates are substantially similar to those of the several Letters Patent hereinbefore specified. Said bending means are located on the top of a 30 table, 1, which is supported on, and overlies a portion of an oil tank. They comprise, as heretofore, a rigid abutment member, 1^b, supporting abutment members, 9, a flexible resistance member, 7, and a cross-head, 3, actuated by a piston, working in a cylinder, 2, fixed on the table, the outer end of the rod, 2^b, of said piston, being secured to the cross-head. The specified forming mechanism 35 noted is not therefore claimed as of my present invention, and any other suitable and preferred form may be applied without departure therefrom.

40 In accordance with my present invention, an improvement is made in the presser blocks, 4, through which pressure is transmitted from the crosshead, 3, to the spring plates 5, in bending them to the proper forms against the formation plate 6. As most clearly shown in

Figs. 2 and 3, cylindrical seats, 4^a, are formed on the presser blocks, around which are wound coils of wire, 38, whereby they may be converted into electro-magnets. The circuit, 39, of said coils, is connected to an automatic 55 switch, 40, located in position to be opened and closed by the cross-head, 3, in its reciprocating movements, the circuit being closed when the cross-head moves back after forming a spring plate, whereby the magnetized presser blocks draw back with them, the relatively cold formation plate, leaving the spring plate, if at the requisite temperature, on the relatively cool movable table section.

Should the spring plate be at a temperature below that required for its proper hardening in the oil bath, it will also be subject to the magnetic attraction of the presser blocks, and be withdrawn with them and the foundation plate instead of being dropped into the 70 oil tank. A valuable check is provided upon the degree of heating of the spring plates. If desired, the magnetic circuit may be maintained during the operation of the machine, subject to manual control, and the automatic 75 switch may be omitted.

I claim as my invention and desire to secure by Letters Patent:

1. In a spring forming machine, the combination of a flexible resistance member; a 80 formation plate; presser blocks, cooperating with said plate; and means for converting said presser blocks into electro-magnets to prevent release of formed springs at other than tempering temperature.

2. In a spring forming machine, the combination of a flexible resistance member; a 85 formation plate; presser blocks, cooperating with said plate; and intermittently operative means for converting said presser blocks into electro-magnets to prevent release of formed springs at other than tempering temperature.

3. In a spring forming machine, the combination of a flexible resistance member; a 90 formation plate; presser blocks, cooperating with said plate; and magnetic coils on said blocks, for converting them into electro-magnets to prevent release of formed springs at other than tempering temperature.

THOMAS F. BUCKLEY.
